Chas. C. Gill

UNITED STATES PATENT OFFICE.

FRANK A. WEEKS, OF PLAINFIELD, NEW JERSEY.

INKSTAND.

1,272,585.

Specification of Letters Patent. Patented July 16, 1918.

Application filed April 9, 1917. Serial No. 160,636.

To all whom it may concern:

Be it known that I, FRANK A. WEEKS, a citizen of the United States, and a resident of Plainfield, in the county of Union and 5 State of New Jersey, have invented certain new and useful Improvements in Inkstands, of which the following is a specification.

The invention pertains to the class of inkstands comprising a glass base containing 10 the inkwell and a removable composition cover therefor having a hinged member by means of which the dip-opening for the pen may be opened or closed. The invention resides more particularly in a novel construction of the molded composition cover for the 15 inkwell, and said cover comprises a body portion having at its forward end a dip-opening and guide for the pen, and a hinged lid therefor to be opened and closed, as occasion 20 may require, said lid being secured to said body-portion in a novel manner by which the pintle of the hinge is concealed and therefore not permitted to mar the finish of the cover or inkstand as a whole.

25 The inkstand of my invention is of durable and attractive character and quite convenient in use, and the same will be fully understood from the detailed description hereinafter presented, reference being had 30 to the accompanying drawings, in which:

Figure 1 is a top view of an inkstand embodying my invention;

Fig. 2 is a central vertical longitudinal section through the same taken on the dotted 35 line 2—2 of Fig. 1;

Fig. 3 is a top view, on a smaller scale, of the glass base of the inkstand, the cover therefor being omitted;

Fig. 4 is a bottom view of the cover, for 40 the inkstand;

Fig. 5 is a perspective view of the inkstand-cover, less the hinged lid for the dip-opening, and

Fig. 6 is a perspective view of the two 45 parts of the hinged dip-opening cover-portions separated from each other but ready to be assembled on opposite sides of the wire held by the main cover-portion and serving as a pintle for hinging said parts together.

50 In the drawings, 10 designates the glass base, and 11 the cover therefor having a forward hinged lid 12 for a dip-opening 13.

The base 10 contains an elongated inkwell 14 and, for convenience, is preferably formed 55 with a pen-groove or rack 15. The base 10 is one integral slab, and at opposite sides

of the inkwell 14 is formed with raised parallel ribs 16, which serve to position the cover 11 while at the same time permitting said cover to be lifted from the base 10 whenever the well 14 requires replenishing with ink.

The cover 11 comprises a body-portion 17 and said hinged lid 12, and said body-portion has a raised central and rear portion 18 and a lower flat front section 19, at the rear of which are vertical shoulders 20 and which section contains a combined dip-opening and downwardly extending annular conical pen-guide 21 leading to the forward end of the well 14. The pen-guide 21 enters the upper end of the well 14 and at its front edge engages the forward wall of the well to aid in positioning the cover on the base 10 and prevent forward sliding movement of said cover. At its lower side the cover 11 is formed along its edges with a downwardly extending flange 22 which engages the top of the base 10 and encompasses a raised portion 23 whose opposite sides fit on the ribs 16 of the base 10, which ribs lie directly at the inner facing longitudinal sides of the flange 22. The ends of the rear transverse member of the flange 22 are in rear of the rear ends of the ribs 16, and at the front ends of said ribs 16 the flange 22 is configurated to create shoulders 24 adapted to engage said front ends of said ribs and coöperate therewith as stops in preventing rearwardly sliding movement of the cover. Within the inner outline defined by the raised portion 23 at the bottom of the cover 11 is a further raised section 25, which is below the outer raised central and rear portion 18 and to an extent hollows out the same. The portion 18 of the cover is recessed at the central portion of its front edge, as at 26, and between the side walls of this recess extends a wire pintle 27, whose end portions are embedded in the material of the cover 11 during the molding of said cover and therefore concealed, the ends of said wire pintle or rod thus not being permitted to mar the appearance of the cover. The rear edge of the recess 26 is transverse and said edge is undercut downwardly and rearwardly, as at 28, for clearance for the rear edge of the hinged lid 12 during the opening and closing movements of said lid.

The lid 12 follows the general outline of 110 the front portion of the main body of the cover 11 and it is adapted to lie upon the

flat surface 19 of said body and be turned upwardly, when desired, to expose the dip-opening and pen-guide 21. The lid 12 is hinged upon the wire rod or pintle 27, and 5 said lid has a rearwardly extending tongue portion 29 which is adapted to fit within the recess 26 of the main cover portion, as shown in Fig. 1, and has in its lower side a groove 30 to rest upon and encompass the main 10 body of the wire rod or pintle 27, as shown more clearly in Fig. 2. The lid 12 is secured upon the rod or pintle 27 by a supplemental composition block 31, which when the tongue 29 is placed upon the rod or pintle 27 is 15 cemented against the inner face of said tongue, thereby permanently hinging the lid 12. To aid in effectually securing the block 31 against the inner face of the tongue 29, I form said block with projections 32 and the 20 tongue 29 with recesses 33 to receive said projections 32, as shown in Fig. 6. The manner of securing the lid 12 upon the rod or pintle 27 just hereinbefore described permits me to make the main body of the cover 25 11 in one piece and conceal the ends of the rod or pintle 27 within the composition of the cover. At each side of the tongue 29 the rear edges of the lid 12 are, when the lid is in closed position, adapted to fit snugly 30 against the shoulders 20. The undercut 28 at the rear end of the recess 26 in the cover 11 permits of the convenient opening and closing of the lid 12, the rear end of the tongue 29 turning downwardly into said undercut 35 portion during the opening of the lid 12 and ascending up through the same during the closing of said lid. When the lid 12 is in closed position it covers the forward flat portion 19 of the cover and at its outer 40 surface harmonizes with the other portions of the cover so as to present an article which is neat in appearance as well as of practical utility.

The invention pertains more particularly 45 to the cover portion of the inkstand, and the outline of the glass base 10 may vary, at will.

What I claim as my invention and desire to secure by Letters-Patent, is:

50 1. An inkstand comprising a base containing an inkwell and a cover mounted on said base and covering said inkwell and having a raised rear portion and a depressed forward portion above the front end of said 55 inkwell and containing a pen-opening, and said cover also having over its forward depressed portion a hinged lid whose edges follow the general outline of the front portion of the main body of the cover and whose 60 upper surface follows the general outline of the raised rear portion of said cover, and which lid is adapted to lie upon the depressed forward portion of said body and over said pen-opening.

65 2. An inkstand comprising a base contain-

ing an inkwell, a cover mounted on said base and covering said inkwell and having a forward depressed portion containing a pen-opening and rearwardly thereof a raised portion recessed in its front edge, a pintle 70 crossing said recess, and a lid hinged on said pintle and adapted to rest upon said depressed portion of the cover and close said opening.

3. An inkstand comprising a base containing 75 an inkwell, a cover mounted on said base and covering said inkwell and having a forward depressed portion containing a pen-opening and rearwardly thereof a raised portion recessed in its front edge, a pintle 80 crossing said recess, and a lid adapted to rest upon said depressed portion of the cover and close said opening, said lid having a tongue within said recess and hinged on said pintle and a supplemental block secured thereto and crossing said pintle on the side thereof opposite to the body of the tongue, whereby said lid is securely connected with the pintle.

4. An inkstand comprising a base containing 90 an inkwell, a cover mounted on said base and covering said inkwell and having a forward depressed portion containing a pen-opening and rearwardly thereof a raised portion recessed in its front edge and 95 presenting shoulders at opposite sides of said recess, a pintle crossing said recess and at its ends embedded within the material of said cover, and a lid hinged on said pintle and adapted to rest upon said depressed portion of the cover and close said opening, said lid having a tongue adapted to said recess and pintle and portions at opposite sides of said tongue to match said shoulders.

5. An inkstand comprising a base containing 105 an inkwell, a cover mounted on said base and covering said inkwell and having a forward depressed portion containing a pen-opening and rearwardly thereof a raised portion recessed in its front edge and presenting shoulders at opposite sides of said recess, a pintle crossing said recess and at its ends embedded within the material of said cover, and a lid hinged on said pintle and adapted to rest upon said depressed portion of the cover and close said opening, 110 said lid having a tongue adapted to said recess and pintle and portions at opposite sides of said tongue to match said shoulders, and the connection of the lid to said pintle being by means of a groove in said tongue receiving said pintle and a supplemental block secured to said tongue and crossing said pintle at the side thereof opposite to the body of said tongue.

6. An inkstand comprising a base containing 115 an inkwell and a cover mounted on said base and covering said inkwell and having a raised rear portion and a depressed forward portion above the front end of said 120

inkwell and containing a pen-opening and having a pen-guide extending downwardly from said opening into the well, and said cover also having over its forward depressed portion a hinged lid whose edges follow the general outline of the front portion of the main body of the cover and whose upper surface follows the general outline of the raised rear portion of said cover, and which lid is adapted to lie upon the depressed forward portion of said body and over said pen-opening.

7. An inkstand comprising a base containing an inkwell, a cover mounted on said base over said inkwell, and a lid hinged to said cover for closing the pen-opening to said well, said cover having a recess in its

forward portion, and a pintle crossing said recess, and said lid having a tongue within said recess mounted on said pintle and a supplemental block secured thereto and crossing said pintle on the side thereof opposite to the body of the tongue, whereby the lid is securely connected with said pintle and the end portions of the pintle are concealed.

Signed at New York city, in the county of New York, and State of New York, this 6th day of April, A. D. 1917.

FRANK A. WEEKS.
